NECKLACE

Vernon P. Peck and Stanley O. Shinkawa, both of International Market Place, Honolulu, Hawaii

Filed June 9, 1961, Ser. No. 65,524

Term of patent 14 years

(Cl. D45—16)

FIG. 1.

FIG. 5.

FIG. 6.

FIG. 3. FIG. 2. FIG. 4.

FIGURE 1 is a top plan view of a necklace showing our new design;

FIGURE 2 is a front elevational view of one of the links thereof;

FIGURE 3 is a left-side edge view of the link shown in FIGURE 2;

FIGURE 4 is a right-hand edge view of the link shown in FIGURE 2;

FIGURE 5 is a top plan view of the link shown in FIGURE 2; and

FIGURE 6 is a bottom plan view of the link shown in FIGURE 2.

The alternate links of the necklace are substantially a mirror image of the link shown in FIGURE 2.

We claim:

The ornamental design for a necklace, as shown and described.
